UNITED STATES PATENT OFFICE.

WILLIAM E. GIBBS, OF PLAINFIELD, NEW JERSEY, ASSIGNOR TO GIBBS COMPANY, OF PLAINFIELD, NEW JERSEY, A CORPORATION OF NEW JERSEY.

APPARATUS FOR ELECTROLYTIC PRODUCTION OF WIRE.

1,120,191.

Specification of Letters Patent.

Patented Dec. 8, 1914.

Application filed April 4, 1912. Serial No. 688,349.

To all whom it may concern:

Be it known that I, WILLIAM E. GIBBS, a citizen of the United States, and a resident of Plainfield, in the county of Union and 5 State of New Jersey, have invented certain new and useful Improvements in Apparatus for Electrolytic Production of Wire, of which the following is a full and clear specification.

10 My invention relates to the production of wire by electrodeposition and drawing as distinguished from the usual practice of forming a wire rod in the rolling mill and drawing the rod down to wire.

15 The apparatus is especially suitable for the production of copper wire and will be described more particularly with reference to this kind of wire, it being understood, however, that the principles of my invention 20 may be employed in other analogous uses, employing other metals or combinations of metals as when producing so-called bi-metallic wire.

An important object of my invention is 25 to produce a wire of high electrical conductivity, and of superior quality which results from the exclusion therefrom of the various impurities (such as copper oxids) common in wire made by the usual processes of rolling and drawing from cast copper wire bars.

I make marked saving over the present methods of producing wire by substituting two simple operations; namely, plating and 35 drawing, which may be carried out either jointly, as shown in the diagrams, or separately if preferred, for the operations of heating, rolling, pickling and drawing, as carried out in present practice, this saving 40 being particularly marked in the production of fine wire. I also may save part of the present cost of refining copper, as cathode copper, as produced at present in the customary process for the refining of 45 copper, is entirely suitable for anodes in my process, and under some conditions impure anode copper can be used, the refining being done in the bath from which the wire is plated.

50 A further object of my invention is to considerably lessen the cost of production of such wire, partly by the use of automatic devices in certain portions of the mechanism to insure continuity of the operations and partly by other automatic de-

vices which act to control or stop the process in case of breakage of the wire. By means of such automatic devices a group of a number of machines may be operated by one attendant thus greatly reducing the cost 60 of labor per pound of wire produced.

Another important object of my invention is to convert into wire so large a proportion of the copper used as anodes, that the production of scrap copper shall be reduced to a minimum and that the small proportion of scrap which is formed shall consist of undissolved anodes upon which no energy has been expended.

Under the present methods of wire making the scrap forms an important item of expense, the more so as it accumulates at every stage of the process and has had various amounts of energy and labor expended on it. Therefore, in addition to the cost of 70 getting it back into the form of copper bar, there must be added the further charge represented in the time and labor consumed in bringing it to the stage from which it was rejected as scrap.

A further object of my invention is to avoid the loss of copper which occurs in the usual rolling and drawing process due to the formation of oxid scale at the rolling temperature and dust or other finely subdivided material which is a constant source 85 of considerable loss in every rolling mill plant.

Many proposals for the production of copper wire by electrolytic deposition have 90 been made in past years, and it has been recognized for some time that there are a number of difficulties inherent to an electrolytic process for this purpose which must be overcome before commercial success can be 95 gained. It is thought that the essential features of the apparatus which I shall describe and the purpose of the various parts will be better understood if a few of the more important considerations involved in 100 the successful production of copper wire by electrolysis are briefly outlined.

The structure of the electrolytic wire as it comes from the depositing bath must be homogeneous and its surface, which should 105 be as smooth as is possible under the circumstances, should be of uniform texture, that is, the surface should be of a velvety grain, free from protruding crystals, lumps or warts. It is well known that copper may 110

be deposited in a thin layer of the desired character, but that after a time as the layer grows thicker, imperfections such as those mentioned appear at irregular intervals upon it. Such wire cannot be satisfactorily drawn. For this reason the wire must receive a deposit limited in thickness and time by the appearance of blemishes. Before these appear, the wire must be drawn through a die in order to renew its surface, when another layer of copper may be deposited on it and so on indefinitely. The wire must be kept in motion through the electrolyte, so that every part of it passes through the same cycle of operations, and no part of it must remain at rest on any supporting or guiding roller, for if it does, the deposit will not be uniform in thickness. I meet these two conditions by carrying the wire through the electrolytic vat, as shown later, on a series of rollers at a constant speed which is such that any point of the wire will enter the electrolyte and leave it again before the deposited layer of copper shows signs of irregularities. For a wire of .025 inch in diameter this time may be about an hour, during which a point on the wire travels about 2000 feet and increases in diameter to .029 inch. The deposit must be ductile and soft. The resistance of the electrolyte must be low, so that the voltage between the anodes and the wire may not approach the value, at which gas is liberated on the wire, which would produce an uneven coating as well as waste energy, and because the conductivity of the electrolyte determines the amount of copper deposited per unit of electrical energy. I meet the last two conditions by using an electrolyte which contains about 3.5% of copper and about 10% of sulfuric acid, maintaining the electrolyte at a temperature of about 140° F. and keeping it in motion as shown later.

During the process of deposition, a dark, powdery coating, called anode slime, forms on the anodes when cast copper anodes are used. Specks of the coating, which consist of finely divided particles of copper and any insoluble impurities which are contained in the anodes, have a tendency to attach themselves to the wire, where they form nuclei for the growth of warts or crystals. In order to prevent this action the electrolyte is arranged to flow in a cyclic manner into the ends of each depositing vat, thence along the wire and past the anodes to the bottom of the vat, whence a pipe near the center leads it to a pump and filter or other separator. Hence clean electrolyte is always entering the vat, washing the wire and anodes and carrying the impurities away.

In order to get the largest output of wire from a machine of a given size the density of the depositing current should be

as great as possible. Yet it must be kept below that value at which the deposit begins to lose its ductility. A low current density deposits the copper at a less expenditure of energy per pound, but on the other hand the whole plant has to be larger and more costly, so that the interest on the investment may more than balance the gain. I have found a current density of about 50 amperes per square foot a good mean value. With anodes one inch from the wire and a solution such as described, I get an output of more than six pounds of deposited copper per kilowatt-hour of current delivered to the vat. The wire which enters the electrolyte has always, in this process, previously passed through a drawing die, whereby its surface is burnished and it always carries a thin film of the lubricant used on the die. Not only must the wire be made chemically clean and every trace of oxid removed from its surface, but the surface itself must be modified in order that the copper which is next deposited thereon may form an adherent coating. Deposited copper will not unite with a burnished surface. I therefore pass the wire through a boiling alkaline solution to remove any grease, thence over a pulley where a stream of water plays on it, and thence through a small tank containing the acid copper-sulfate electrolyte and a copper plate. In this tank, however, the direction of the current is reversed, whereby the wire becomes the anode and is slightly etched, so that the crystalline character of surface necessary to retain a deposit of copper is given to it. Any trace of oxid on the surface is taken up by the free acid in the electrolyte. Thence the wire passes through a tube into the depositing vat, passing beneath the incoming stream of clean electrolyte, which washes away any anode slime that may have formed on it during its passage through the etching bath.

After the wire enters the depositing vat, it is desirable to carry the convolutions of the wire on copper or other electrically conductive rollers, which form one pole of the electro-plating source of current. The obvious device of glass or porcelain rollers and brushes for conveying the current to the wire fails because if the wire has a sliding contact with a brush or the like, particles of copper are ground off the brush and the wire, and form nuclei for irregular growths. For a similar reason the guides which keep the wires evenly spaced, must be grooved rollers or the like, for all comb-like guides either grind or, if they are hard like glass, polish the wire and prevent adhesion of the deposit. Moreover, the hardest glass is soon cut into grooves by the friction of the slightly rough surface of the wire. Since the supporting rollers in the vat must be of

metal, it is necessary to protect them against continual growth by deposition of copper. For this reason I isolate them from the central portion of the vat by partitions of non-conducting material, preferably glass, leaving only narrow slots through which the wires pass. By this means I entirely prevent the deposition of copper upon said rollers. The same statement applies to the guide rollers when these are of metal.

In what has been said about the circulation of the electrolyte in the vat, it will be seen that the filtered solution enters the isolated compartment at each end of the vat, and that it flows out into the central part of the vat by way of the same slots through which the wires pass. Consequently there is always a brisk current of clear solution flowing over the rollers, which keeps them clean and keeps impurities from entering the roller compartments, where they would be caught by the rollers and forced into close contact with the wire. The anodes are placed as near the wire as may be without danger of the wire touching them or of the formation of crystals which might bridge the space. By hanging a set of anodes on each side of the sheet of moving wire I am able to reduce the resistance of the system to two-thirds of that which it has when only a single set of anodes is used, and I also get a more efficient scouring effect from the circulation of the electrolyte. As has been noted, every device which lowers the resistance of the system increases the output of wire per unit of energy expended.

My invention provides for the continuous feeding of a considerable length of wire through an electrolytic depositing vat in a series of loops passing around two rollers in such manner that each loop will be kept from contact with its fellows and at the same time held in position for receiving a uniform deposit of copper. In addition to this the wire must enter and leave the vat under constant tension, otherwise certain loops will become loose and tangle, or will become so tight that the wire breaks. On issuing from the depositing vat the wire must be washed to remove the electrolyte which would corrode the winding machinery, thence it should go to the outgoing tension control, and a device to regulate the speed of the winding block, whereby any change in the rate of deposition changes the speed at which the wire is drawn. Thence it must pass through a lubricating bath and through the drawing die which reduces it to its original size again, after which it is coiled up on the block, and, when the machine is arranged to operate cyclically, it may be led through an unwinding device and thence back to the vat by way of the ingoing tension device and the cleaning and etching tanks. In the preferred apparatus,

the rollers which support the wire, during its passage through the depositing vat, revolve upon anti-friction bearings, on vertical shafts which depend from a horizontal beam arranged at such a height above the vat that the wire is stretched in two broad vertical sheets below the surface of the electrolyte. By means of adjusting screws, the distance between the two rollers may be altered, and they may be set parallel or at a slight angle to each other.

When the machine is in operation, the wire that leaves the vat, is, by reason of the deposited copper, somewhat greater in diameter than that which enters, and as the deposition is at a constant rate, it will be seen that the wire in the vat is evenly tapered from its entering to its outgoing end. In order to give a uniform motion to all parts of the wire and help to keep its tension the same for its whole length, the rollers may be very slightly tapered, being smaller at the outgoing end of the wire. But in originally stringing up a new machine it is necessary to use wire of uniform diameter, which would not wind smoothly on the rollers under the above conditions. By giving the axes of the rollers a slight inclination I find that the straight wire can be wound on smoothly. When the wire is lowered into the hot electrolyte it expands, and it is then necessary to take up the slack by means of the screws which separate the rollers. For the first few hours of operation it is necessary to manipulate one or the other adjustment until conditions become normal, and generally to reject the wire which was wound on the machine by hand, because the deposited copper will not stick to it. The machine may be stopped at any time for removal of wire which has accumulated on the block, and since, after passing through the etching bath, the wire is not again exposed to the air until it leaves the depositing vat, the machine may be restarted without fear of a defective spot in the wire. The depositing current is carried from the generator to a framework which holds the anodes, thence through the electrolyte to the wire and thence by brushes on the axles of the rollers back to the generator.

Further mechanical features of my invention relate to safety devices intended to render the operation of the apparatus automatic as far as possible and to prevent tangling of the wire in the vat in case the wire should break at any point. These devices will be described more in detail in connection with the drawings which illustrate my invention.

In the drawings, Figure 1 is a diagrammatic elevation of the essential parts of a complete system for the production of wire by electrolytic deposition, Fig. 2 is a side elevation of a modification of the ingoing

tension control apparatus and safety cutout, Fig. 3 is a perspective thereof, Fig. 4 is a side elevation with parts in section of the washing bath, the plating off or etching bath 5 and the intake end of the main depositing tank, Fig. 5 is a top plan view of the plating off or etching mechanism, Fig. 6 is a bottom plan view of the supporting rolls or drums in the cleaning tank shown in Fig. 4, Fig. 7 10 is a top plan view of the main depositing vat, Fig. 8 is a side elevation of the same with the side and end walls in section, Fig. 9 is a detail plan view with parts in section of a form of guard device for keeping the wire 15 from coming into contact with the anode plates. Fig. 10 is a detail plan view with parts in section of one of the main supporting rolls and a safety throwout operating in conjunction with one of the guide rollers. 20 Fig. 11 is a central vertical section taken longitudinally of the depositing vat of one of the main supporting rolls and its adjustable mounting, Fig. 12 is an end elevation of the same, showing one of the guide rollers, 25 Fig. 13 is a central vertical section through the drawing machine, Fig. 14 is a diagrammatic plan view illustrating the circulation and showing a group of units for the production of wire by electrodeposition, and 30 Fig. 15 is a vertical section and Fig. 16 a plan view of a special form of winding block which may be employed in the drawing machine.

Referring to Fig. 1 it will be seen that the 35 system comprises in general the feeding-in tension control apparatus A, the washing apparatus B, the plating-off or etching apparatus C, the main depositing apparatus D, the outgoing tension control apparatus 40 E, and the winding block and drawing apparatus F. In Fig. 1 I have shown the feeding-in tension control apparatus as comprising in general the idle brake roller or pulley 20, around which the wire passes and 45 from which it runs down to and around a drop pulley 21, from which it runs over a stationary pulley 22 to the preliminary washing apparatus to be described. The brake roller has coöperating with it a 50 weighted brake lever 23 pivoted at 24 and carrying an adjustable counterweight 25 and brake shoe 26 which latter engages the brake pulley 20 or a part connected therewith. Suitably attached to the outer end of the 55 brake lever 23 is a core piece 27 of a solenoid coil 28, which is in circuit through conductors 29 and 30, contact rollers 31 and 32 and resistance pieces 33, 34 and 35 with a source of current 36. The resistance pieces 60 33, 34 and 35 are supported from an arm 37 which depends from the axle or journal 38 of the drop roller 21, so that if the wire is fed too fast the drop pulley 21 descends and cuts out a portion of the resistance pieces 33, 34, thereby strengthening the current pass-

ing through solenoid coil 28, and applying the brake to the brake roller 20. If the wire feeds too slowly the drop pulley 21 ascends and thus adds resistance to the solenoid circuit and weakens the current in the solenoid, 70 thereby relieving the brake roller 20. It will be seen that this tension control thus operates in a continuous manner and tends to maintain a constant rate of feed or admission of the wire. I may employ in lieu of this form of feeding-in tension control apparatus the apparatus illustrated in Figs. 2 and 3. This apparatus is mounted upon the standard 38 and comprises the pulleys 39, 40 and 41, which are analogous in their 75 functions to the pulleys 20, 21 and 22 respectively. The pulley 39 is fixed upon one side of the frame 42 upon a shaft 43 which also has fixed on it a toothed wheel 44. The toothed wheel 44 meshes with a spur gear 45 which is fixed on a shaft 46 journaled in the frame 42 and carrying a brake disk 47. The brake lever 48 is pivoted upon a support 49 projecting from the frame 42, and carries the brake shoe 50, engaging brake wheel 47, 90 and the adjustable counterbalance weight 51. The outer end of the brake lever 48 has attached to it a tension spring 52, the other end of which is suitably secured through a chain or the like 53 to the carriage 54 of the drop pulley 40. Carriage 54 carries a suitable weight 55 and is in the form of a sleeve 95 slidably mounted upon the vertical rod 56 which is secured by brackets 57 and 58 to the main standard 38. The wire passes 100 around the pulley 39, then down and under the drop pulley 40 and up over the guide pulley 41 from which it is led into the washing apparatus as will be described. It will be apparent that the weighted drop pulley 105 40 is supported by the wire and that as the wire feeds faster the drop pulley descends and increases the tension upon the tension spring 52 thus applying the brake shoe 50 more firmly to the brake disk 47 to retard 110 the feed of the wire. As the wire feeds more slowly the drop pulley 40 ascends and relieves the tension on the spring 52 and diminishes the braking effect so that the pulley 39 may revolve faster. The arrangement of the braking action through a geared down system relieves the operation from sudden shock and conduces to a more gradual and even regulation. Mounted above 115 and in the path of the drop pulley carriage 54 is a throw-out switch 59 which normally engages the contact 60. Similarly mounted below the carriage 54 is a throw-out switch 61 which normally engages the contact 62. Contacts 60 and 62 are electrically connected 120 by means of the conductor 63, and leading to the switch arms 59 and 61 are conductors 64 and 65 respectively, which lead to the main driving clutch in the depositing apparatus to be described. Should the feed of 125

the wire stop or slow down below the critical point, due to entanglement or other cause in that portion of the wire which is advancing toward the pulley 39, the drop pulley 40 ascends and throws out the switch 59, thereby disconnecting the main driving clutch and stopping the further operation of the feed. Should the wire break between the winding block and the entrance to the 10 depositing vat the drop pulley 40 falls and throws out the switch 61 which has the same result.

Before the wire is subjected to electro-deposition, it is necessary, as has already 15 been stated, to provide the proper kind of surface so that the deposited copper will adhere firmly. The washing apparatus B and the plating off or etching apparatus C are consequently arranged in the system immediately preceding the main depositing vat and they will now be described with 20 reference to Figs. 1, 4, 5 and 6. From the guide pulley 22 the wire passes under the guide pulley 66 which is mounted upon the beam 67 secured in the uprights 68. A floor or other supporting means 69 is also secured in the uprights 68 and upon it is placed the washing tank 70 in which is maintained a body of alkaline solution 71 25 heated by steam coil 72. Dependent from the beam 67 are a pair of studs or shafts 73, 74 upon which are journaled the supporting rolls or drums 75 and 76 immersed in the bath. From the guide pulley 66 the wire 30 is led around the supporting rolls 75 and 76 a suitable number of turns, the several turns being guided therein by means of suitable guide combs or the like 77 which are suspended from the beam 67. The steam coil 35 72 maintains the alkaline solution at a water boiling temperature, so that any grease which there may be upon the surface of the wire, as for example from the drawing lubricant, is entirely removed. The wire is 40 then taken off around the guide pulley 78 which is also supported upon the beam 67, and passing over the guide pulley 66 is led around a guide pulley 79. The wire is here rinsed to remove the remnant of alkali by 45 means of a stream of water which is delivered upon the wheel from a pipe 80 and drains away through the drain pipe 81. The wire then passes down under a guide pulley 82 which is mounted on a beam 83 50 supported in the uprights 68. Below the beam 83 a floor or other supporting member 84 is secured to the uprights and upon this is disposed the electrolytic bath tank 85 which contains the bath 86 for plating off 55 or etching. Shafts or studs 87 and 88 have journaled on them the electrically conductive supporting rolls or drums 89 and 90 immersed in the electrolytic bath 86 and around them the wire passes a number of 60 85 times through the insulating guides 91 and

92, which protect said drums from electrolytic action. A copper plate 93 is suitably supported in the bath 86 within the space inclosed by the wire and is connected by binding post 94 with a source of current, so 70 as to form a cathode. The supporting rolls or drums 89 and 90 are suitably connected with the other pole of the circuit so that the wire forms the anode and plating off from the wire to the copper plate occurs, thus removing any oxid and etching the surface of the wire. The wire is then in condition for 75 receiving the deposit of copper and preferably I introduce it into the depositing tank without exposing it to the atmosphere. For 80 this purpose I provide a pipe 95 of insulating material such as rubber, which leads from an outlet opening 96 of the plating off tank to an inlet opening 97 of the depositing tank 98, below the level of the liquid in 85 the two tanks.

I prefer to mount all of the operating parts of the depositing apparatus so that they may be moved as a unit to introduce the wire, anode plates and associated parts 90 into the tank or to withdraw them therefrom. Accordingly a pair of channel beams 99 and 100 are supported upon suitable uprights 101 and 102, and extend longitudinally over the tank 98. Mounted between 95 the channel beams 99 and 100 is the sleeve 103, the construction of which is illustrated in detail in Fig. 11. Referring to Fig. 11, it will be seen that the upper portion or head of the sleeve 103 has disposed upon 100 it a bearing ring 104 upon which run the thrust bearings 105. A bearing collar 106 rests upon the bearings 105 and is fixed to a rotary shaft 107 which is disposed within the bearing ring 104 and sleeve 103. A 105 flanged collar 108 is secured on the lower end of the shaft 107 immediately beneath the sleeve 103 and to it is secured, by means of screws 109, a hollow cylinder 110 which is closed at the bottom and open at the top. 110 Bearing rings 111 and 112 are secured respectively to the sleeve 103 and cylinder 110, and between them are the ball bearings 113. Similar bearing rings 114, 115 and ball bearings 116 are disposed at the lower end of the 115 sleeve 103, so that the cylinder 110 rotates freely about the sleeve 103. A collar 117 fits loosely around the sleeve 103 and is secured upon the cylinder 110, the joint being provided with an insulating packing 118. The collar 117 is preferably of lead as the electrolyte does not creep by capillary attraction on a lead surface, and thus I provide against the entrance of the liquid or 120 crystals unto the inner construction of the supporting roll. The supporting roll at the outgoing end of the tank is preferably arranged so as to be adjustable in angle and distance from the other roll, to accommodate the varying tension in the wire due to 125 130

the increase in size in its passage through the tank, and its expansion when lowered into the hot liquid. As already explained the wire becomes thicker and thicker as it 5 advances and hence the tension near the bottom of the roll, if the two supporting rolls were exactly parallel, would be much greater than that at the top. On the other hand when the wire is first introduced into the 10 tank upon the commencement of operations, it is of equal thickness throughout. To secure these adjustments the sleeve 103, which acts as a support for the roll 110, is provided with the head 119 through which 15 passes the supporting bolt 120 which rests in slots 121 formed in the channel beams 99 and 100. A vertical slot 122 is formed in the head portion 119 of the supporting sleeve 103 and through it passes a second 20 bolt 123 which extends through longitudinal slots 124 in the channel beams and rests in the two arms of a yoke 125 which is slideable longitudinally along the beams. By loosening the nuts of bolts 120 and 123 the sup- 25 porting roll 110 may thus be moved toward or away from the supporting roll at the opposite ends of the tank, and to effect this movement I provide an adjusting screw 126 which operates against a cross piece 127 se- 30 cured on the ends of the channel beams. The angular adjustment is provided for by a projecting lug or nose 128 on the head portion 119 of the supporting sleeve 103 against which operates an adjustment screw 35 129 secured in a plate 130 extending across the top of the channel beams. The operation of the adjusting screw 129 thus swings the shaft 107 through a slight angle about the supporting bolt 120. The supporting 40 shaft 107, the bearing collar 106 the flanged collar 108 and the hollow cylinder 110 are all of electrically conductive material, so as to lead the current from the wire which runs upon the cylinder. Brushes 131 which 45 bear against the collar 106 are connected with the negative side of the source of current by the conducting segment 132 and conductor 133.

At the feeding-in end of the tank I ar- 50 range the supporting roll 134 which is similar in construction and mounting to the supporting roll at the other end of the tank, with the exception that the adjustments referred to are unnecessary in case of this roll. 55 The driving power is, however, applied at this end of the tank, and I, therefore, provide the rotary shaft with an extension 135 upon which is fixed a bevel gear 136 running in mesh with a bevel gear 137 which is 60 free on the drive shaft 138 receiving the power through belt wheel 139. In order to couple the bevel gear 137 with the drive shaft 138 I preferably employ an electro- 65 magnetic clutch, one member 140 of which is fixed to the bevel gear 137 and the other

member 141 of which is splined to the drive shaft 138. During the normal operation of the apparatus current is supplied to the clutch by contact rings 142 and 143 which are engaged by brushes 144 and 145 to which 70 are connected the conductors 64 and 65, referred to in connection with Figs. 2 and 3.

From the plating off or etching tank previously described, the wire is led on to the supporting rolls under a guide pulley 146 75 supported from the tank wall, and over the guide pulley 147 which is journaled in the hanger 148 dependent from the channel beam 99. This arrangement of guide pulleys provides for the removal of the sup- 80 porting rolls and associated parts from the tank without disturbing the position of the turns of wire upon the rolls. Four rows of anode plates 149 are arranged in pairs to form a lane at each side through which 85 the wire travels so that it is subjected to deposition at both sides. These are supported from conducting arms 150 to which the positive pole of the source of current is connected. In order that the anode plates may 90 with safety be placed at a minimum distance from the wire I may employ glass or other non-conducting rods, rollers or the like 151, forming guards or fenders which prevent the contact of the wire with the 95 anode plates 149 as illustrated in the detail view Fig. 9.

In order to safely accommodate as many turns of the wire as possible upon the sup- 100 porting rolls it is necessary to provide spe- 105 cial guides so that each turn of the wire is kept clear of those adjacent to it and de- 110 livered to its proper place on the rolls. For this purpose I provide adjacent to each supporting roll, at the side where the wire 115 is running on, a grooved idle roller 152 which turns freely upon an arbor 153 sup- 120 ported in block 154 which is clamped on to the bottom of the channel beams 99 and 100 by bolts 155 and 156. The grooved roller 152 thus spaces the turns of wire upon the supporting roll. Adjacent to the grooved roller 152 I mount a sleeve or the like 157 which is free to turn with slight friction upon the rod 158 fixed in the block 154. The 125 sleeve 157 has a pair of jaws 159 in which is mounted a glass or other suitable bar 160 in close proximity to the grooved roller 152 but not in engagement therewith. The sleeve 157 has projecting from it a finger 161 which rests normally against an ad- 130 justable stop bolt 162, and carries a bridge piece 163 which is normally held in contact with the contact pieces 164 and 165 of the circuit which leads through the main driv- 135 ing clutch shown in Fig. 7. During the normal operation of the parts, the wire passes through the grooves of the grooved roller 152 which turns freely upon the ar- 140 bor 158, but does not come in contact with 145

the glass bar 160 so that the sleeve 157 remains stationary. Should the tension of any turn of wire become so low as to permit it to sag and run out of its groove 5 on the roller 152, the wire becomes wedged between the roller and the bar 160 and turns the sleeve 157 upon its supporting rod, thus opening the circuit through the contact pieces 164 and 165 and deenergizing the 10 main driving clutch so that the machine is stopped. The same result occurs if the wire breaks or becomes snarled or has any abnormal projection upon its surface which would interfere with the proper travel of 15 the wire through the grooves in the roller 152.

In view of the fact that the current is led from the wire by way of the supporting rolls, provision must be made against any 20 deposition of copper from taking place upon them or upon the conducting parts with which the wire comes in contact. For this reason and for purposes of circulation, as will hereinafter appear, I screen off by 25 suitable insulating means the two ends of the tank beyond the space occupied by the anode plates 149. A glass lining 166 is placed upon the floor and the end and side walls at each end of the tank. Suspended 30 from a frame 167 and cemented therein are a pair of inner parallel glass plates 168 and outer parallel glass plates 169, arranged so that the wire has just sufficient space between the plates 168 and 169 at each 35 side to pass through without rubbing. Also cemented into the frame 167 are the inner transverse glass plate 170 and the outer transverse glass plates 171, the plates 171 being at right angles to the plates 169 to 40 serve with them as an inner support for diagonal glass plates 172, the outer ends of which are retained by the lugs 173 or other suitable means. By this construction it is apparent that the only communication be- 45 tween the space at each end of the tank and the main inner space where the deposition takes place is through the narrow slots or passageways through which the wire runs. The parallel plates 168 and 169 serve the 50 purpose of elongating this space so as to increase the ohmic resistance through the electrolyte therein, and to confine and direct the circulation of the electrolyte, as will be explained, for a suitable distance along the 55 wire.

The apparatus suspended in the tank from the channel beams 99 and 100 is normally held as a unit in the proper position by pegs or the like 174 inserted in the up- 60 rights 101 and 102, upon which the channel irons rest. For raising the apparatus from the tank any suitable means such as eye-bolt 175 may be provided on the frame work to attach a hoisting cable or other desired 65 means, and the apparatus may thus be lifted

and if desired permitted to rest out of the solution, upon pegs inserted in the upper perforations 176 of the uprights 101 and 102. The electrolytic bath is introduced into the insulated compartment at each end 70 of the tank through a supply pipe 177. From each compartment passes through the restricted passageways between the plates 168 and 169 to the exterior or depositing portion of the vat, and is withdrawn 75 through the outlet pipe 178. The liquid thus washes the wire while passing through the restricted passageways between the plates referred to, and tends to prevent any 80 of the suspended particles of undissolved matter from adhering to the wire, or being carried into contact with the supporting rolls, where they would tend to interfere with the proper feed of the wire. The direction of circulation being all toward the 85 center of the vat, the undissolved matter is continuously taken off with the solution and withdrawn through the outlet pipe 178. I prefer to provide for the settling, filtration 90 or other clarification of the bath outside of the depositing tank, somewhere between the outlet 178 and inlet 177. The heating of the solution is also accomplished better outside inasmuch as the application of heat within the depositing vat might interfere with the preferred circulation of the bath. The plates 168 and 169 serve to direct the fresh clarified solution into the lanes formed between the two rows of anode plates, so that the space in which the wire 100 travels and receives its deposit is kept relatively free of suspended undissolved particles, while the main body of the solution being more nearly at rest, facilitates the settling out of the suspended matter, so that it 105 is taken off in the manner described through the outlet pipe 178. The clarification and heating of the solution, referred to above, are illustrated in diagram in Fig. 14, which also serves as an illustration of the group- 110 ing together of several wire making units. Referring to this figure, it will be seen that the circulation takes place through the inlet pipes 177 and depositing tanks D, outlet pipes 178, the common outlet conduit 179, 115 the heating tank 180, supplied with heat by steam coil 181 or the like, pump 182, return pipes 183 branching therefrom, filters or other clarifying devices 184 and common supply pipes 185 from which lead the individual supply pipes 177. 120

Having passed through the depositing vat and received its coating of new copper, the wire passes off under a guide pulley 186 and out over a guide pulley 187, from which it passes under a guide pulley 188 immersed in water 189 where it is washed of any remaining sulfate solution. The wire is now in condition for drawing, to convert its increment in diameter to a lengthwise incre- 130

ment of wire. It may be removed and drawn independently of the depositing step, but it is usually preferable to draw it as it comes from the depositing tank. The drawing of the wire in continuity with the deposition of copper upon the core involves a number of mechanical considerations for which provision must be made. The return of the wire from the drawing machine in a continuous manner necessitates additional expedients. In the first place it is difficult to so regulate the speed of drawing the rate of deposition and the speed of travel of the wire through the depositing vat as to keep them in equilibrium. It is therefore necessary to have the operation of the drawing machine dependent upon a tension control interposed between the depositing vat and the drawing plate. In passing through the draw plate the wire receives a considerable lengthwise increment so that the winding block must be capable of taking on wire at greater speed than the wire is removed from it for return to the deposition. The tension control of the drawing machine is illustrated diagrammatically in Fig. 1. The wire as it leaves the bath 189 is led over a pair of guide pulleys 190 and 190^a from which a loop is taken under a drop pulley 191. The wire then passes over the guide pulley 192 and under the guide pulley 193 to the drawing machine which will be described. A gravity piece 194 hangs from the drop pulley 191, so that the tension of the wire as it issues from the depositing tank is kept constant. The gravity piece is constructed with resistance pieces 195 bridged by conductor 196, insulating portion 197 and conducting portion 198. Contact rollers 199 normally engage resistance pieces 195, thus regulating the current from battery 200 or the like through conductors 201, 202, 203 and 204 to a clutch 205 of the drawing machine which will be described more in detail. Contact rollers 206 normally engage the insulating portion 197 of the gravity piece, thus keeping open the circuit from the battery 200 through conductors 207, 208, 209 and 210 to the drawing machine brake 211 which will be described further. As the drawing machine tends to take the wire faster than it issues from the depositing vat the gravity piece 194 ascends, thus increasing the effective length of the resistance rods 195 and reducing the current in the drawing machine clutch 205, whereupon the drawing machine slows down. Should the drawing machine still take the wire faster than the depositing apparatus gives it up, the gravity piece 194 continues its ascent until the resistance pieces 195 moves entirely clear of the contact rollers 199, which latter then engage the non-conducting portion 197, so that the clutch is entirely

disconnected and the contact rollers 206 of the magnetic brake 211 contact with the conducting portion 198, thereby sending the current through the magnetic brake and applying the maximum braking force. This operation is sometimes occasioned by residual magnetism of the magnetic clutch 205 or the momentum of the moving parts. Should the drawing machine not operate fast enough to take up the wire delivered by the depositing apparatus, the gravity piece 194 descends thus shortening the effective length of the resistance pieces 195 and increasing the current through the magnetic clutch 205, whereupon the drawing machine speeds up. In practice the speed of the drawing machine is preferably so regulated as to take the wire up at a slightly excessive speed, so that the automatic regulation is mainly necessary to slow it down. I also arrange a positive throw-out for the main driving clutch in connection with the out-going tension control described. This device may comprise for example the chain or cord 212 which runs over guide pulleys 213 and 214 and is connected at one end with an eyelet 215 of the gravity piece 194 and bears at its other end a counterweight 216. The cord 212 passes through the perforated or slotted end 217 of a contact lever 218 which is pivoted at 219 and normally closes the main driving clutch circuit through the terminals 220 and 221. Should the wire break anywhere between the depositing vat and the drawing machine the drop piece 190 falls and thus the counterweight 216 ascends and throws the pivoted contact lever 218 out of engagement with the terminal 221 thereby opening the circuit through the main driving clutch. The drawing machine is illustrated in vertical section in Fig. 13. The wire is taken in under the guide pulley 222 and a drop pulley 223 of an automatic gripping lever 224 which is pivoted in a bracket 225 and operates against a flange 226 thereof. Normally the drop pulley 223 is supported by the wire which is under tension, so that its grip lever 224 is held clear of the wire. Should the wire break at the draw plate its tension is relaxed, so that the drop pulley 223 swings downward thus bringing the grip lever 224 into engagement with the wire and holding the wire securely against the flange 226 to prevent it from running back through the tension control device. From the pulley 223 the wire passes under a guide pulley 227 which is journaled in a bracket 228 and immersed in a vessel 229 which supplies the lubricant for the draw-plate. Brackets 225 and 228 are secured to a cross brace 230 in the main frame 231 of the drawing machine. The cross brace 230 is perforated at 232 to permit the passage of the wire on its way to the draw plate which is shown at 233. Draw

plate 233 is positioned against the lower end of a shaft 234 which is perforated longitudinally at 235 and recessed longitudinally at 236. Shaft 234 has a lower bearing in a cross brace 237 upon which runs the thrust bearing collar 238 secured on the shaft. The upper bearing of the shaft 234 is in a stationary gear plate 239 which rests upon a plate 240 to which the uprights of the main frame are secured. Clamped upon the shaft 234 above the gear plate 239 is a slotted revolving arm 241. Tightening bolts 242 and 243 passing through the slotted portion of the revolving arm serve to secure it in place upon the shaft. The bolt 243 also serves as a journal for a guide pulley 244 which guides the wire longitudinally of the shaft as it comes from the draw plate 233. One end of the slotted arm 241 carries a guide pulley 245 which is journaled in a hollow fork 246 adjustably secured at the proper angle in the socket 247 by means of a set screw or the like 248. The other end of the slotted arm 244 has journaled in it a shaft 249 which has fixed on it a gear wheel 250 in mesh with the fixed gear plate 239 and a gear wheel 251 in mesh with a gear plate 252 which surrounds shaft 234 above the slotted arm 241. The gear plate 252 is thus held against rotation and secured to it is the block 253 upon which the wire is to be coiled. The block rests upon the upper end of shaft 234 and thus supports the gear plate 252. A tilting ring 254 surrounds the base of the block 253 and is tilted at the proper angle by means of a roller 255 (see Fig. 1), which is also carried by the revolving arm 241, to facilitate the laying of the wire at the bottom of the coil already formed on the block. As the arm 241 revolves, the wire which is led from the guide pulley 243 through the hollow fork 246 and around the guide pulley 245 is carried around the block and thus is wound thereon, the block being held stationary by means of the gear plate 252 to which it is secured. The operation of the tilting ring 244 always provides a space below the lowermost turn of wire in the coil and into this space the wire is directed by the guide pulley 245 of the revolving arm. The effect of this is to build up the coil from below and constantly crowd the wire toward the upper end of the block, so that the upper turns of the coil are free to be taken off as will be described later.

Power is applied to the shaft 234 from a belt pulley 256 on shaft 257 journaled in bearing 258 and having fixed on its inner end a bevel gear 259. Bevel gear 259 meshes with a bevel gear 260 which is free to turn upon the shaft 234 and supported thereon by the bearing collar 261 which is fixed on the shaft 234. Splined on the shaft 234 above the bevel gear 260 is the field piece 262 of the magnetic clutch which has a magnet

coil 263 supplied with current through the contact rings 264 and brushes 265. The field piece 262 coöperates with an armature piece 266 which may be formed integral with the bevel gear 260 so that when the coil 263 is energized the rotation of the bevel gear 260 is imparted to the shaft through the field piece 262 splined thereon. To retard the drawing apparatus, I provide a magnetic brake comprising the stationary field pieces 267 and the revolving armature 268 which is splined on the shaft 234 and bears upon the bearing collar 269 secured on the shaft 234. When the magnetic brake is energized the rotation of the shaft is thus retarded. Surrounding the upper portion of the stationary block 253 and resting upon the coil of wire thereon is a retaining ring 270. A guide pulley 271 is mounted in a fork 272 which is journaled in a revolving arm 273 pivoted in the end plate or cap 274 of the block 253. The fork 272 has extending from its outer ends the grooved fingers 275 between which the wire is led to the guide pulley 271. From the guide pulley 271 the wire passes under a guide pulley 276 which is mounted in a fork 277 secured to or integral with the revolving arm 273.

Referring to Fig. 1 it will be seen that the wire is drawn, by the supporting rollers in the depositing tank, through the leading off guide device of the winding block 253 and over a guide pulley 278. The retaining ring 270 shown in Figs. 1 and 13 operates to prevent the coil of wire on the block 253 from becoming tangled and guides the wire from the coil to the guide pulley 271, which latter, with its supporting device, thus revolves about the block as the wire is being drawn off. In this connection it should be pointed out that the draw plate 233 being in engagement with the revolving shaft 234 removes the torsion or twist which the wire receives between the guide pulley 227 and the draw plate, so that the wire which is laid about the block 253 is not under torsional strain. The retaining ring 270 preferably has some freedom or play upon the block 253 and as the wire is withdrawn by the revolving guide devices the ring is tilted. When working with small wire there is some tendency for the loose turns of wire to enter into the space between the retaining ring and the block and interfere with its proper operation. To avoid this difficulty I may employ a slotted or grooved block with a retaining ring having fingers projecting into the slots or grooves of the block. Such a construction is illustrated in Figs. 15 and 16. The block is formed of a base 279 on a reduced portion of which is seated a sleeve or shell 280 which is provided with a suitable number of slots 281 extending longitudinally of the drum. Surrounding the shell 280 is the retaining ring 282 which has pins or the like 283 threaded

into its inner face and projecting into the slots 281 of the shell. The pins 283 thus prevent the entrance of the wire into the space between the shell and ring.

5 In operation, the increment of wire accumulates upon the winding block. When the block is full, the wire is cut above the block, the unwinding device is removed and all but a few turns of the wire are lifted off the 10 block in a compact coil. The wire is then cut below the coil the unwinding device replaced, the end of the wire remaining on the block is threaded through its pulleys and brazed to the trailing end of the cut wire. 15 The movement of the wire must be stopped for this purpose, but the operation is so quickly done that it is not necessary to interrupt the process of deposition. Consequently there is no loss in the efficiency of 20 the process due to removal of finished wire.

What I claim is:

1. A system of the character described, comprising in combination a depositing apparatus, a drawing apparatus receiving the 25 wire therefrom, and automatic means for maintaining the wire at uniform tension between the depositing apparatus and drawing apparatus and controlling the operation of said drawing apparatus.

30 2. A system of the character described, comprising in combination a depositing apparatus, a drawing apparatus, means for leading the wire from the depositing apparatus to the drawing apparatus and from the 35 drawing apparatus back to the depositing apparatus, and automatic means for regulating the tension of the wire as it enters and leaves the depositing apparatus.

3. A system of the character described, 40 comprising in combination a depositing apparatus, means for properly supporting a supply of wire for the apparatus, means for leading the wire from the wire supply means to the depositing apparatus, and automatic 45 means for regulating the speed of the wire from the supply means to the depositing means and maintaining it at uniform tension.

4. A system of the character described, 45 comprising in combination an electrolytic 50 depositing apparatus having means for supporting a relatively great length of wire, a drawing apparatus and means for leading the wire at uniform tension into and through the depositing apparatus and to the drawing 55 apparatus.

5. A system of the character described, 60 comprising in combination a depositing apparatus, a plating off apparatus, means for supplying current thereto and means for leading the wire continuously through the plating off apparatus and the depositing apparatus while maintaining the wire immersed.

6. A system of the character described, 65 comprising in combination a depositing ap-

paratus, a plating off apparatus and means for moving the wire to said depositing apparatus from said plating off apparatus without exposure to the atmosphere.

7. A system of the character described, 70 comprising in combination a depositing apparatus, a plating off apparatus, and means for leading the wire through the plating off apparatus to the depositing apparatus continuously without exposure to the atmos- 75 phere.

8. A system of the character described, comprising in combination a depositing apparatus, a driving connection therefor, means for leading the wire to the depositing 80 apparatus and automatic means for interrupting said driving connection upon interruption of the supply of wire by said wire leading means.

9. A system of the character described, 85 comprising in combination a depositing apparatus, a driving connection therefor, means for leading the wire to the depositing apparatus and an automatic control device supported by the wire on its way to the depositing apparatus for interrupting said driving connection when the wire being led to the depositing apparatus breaks.

10. A system of the character described, 90 comprising in combination a depositing apparatus, a driving connection therefor, means for leading the wire to the depositing apparatus and an automatic control device supported by the wire on its way to the depositing apparatus for interrupting said 95 driving connection when the tension of the wire being led to the depositing apparatus becomes excessive.

11. A system of the character described, 100 comprising in combination a depositing apparatus, means for properly supporting a supply of wire therefor, means for leading the wire from said supply means to the depositing apparatus, a tension control member suspended in a loop of the wire being 110 led to the depositing apparatus, and a retarding device controlled by the position of said tension control member for regulating the supply of wire to the depositing apparatus.

12. A system of the character described, 115 comprising in combination a depositing apparatus, a drawing apparatus having a driving connection and a brake, means for leading the wire from the depositing apparatus to the drawing apparatus, automatic means for regulating the tension of the wire as it leaves the depositing apparatus, and means governed by said tension regulating means for controlling the operation of said 120 connection and said brake.

13. A system of the character described, comprising in combination a depositing apparatus, a driving connection therefor, a drawing apparatus, means for leading the 130

- wire from the depositing apparatus to the drawing apparatus, automatic means for regulating the tension of the wire as it leaves the depositing apparatus, and means governed by said tension regulating means for disengaging said driving connection when the wire breaks on its way to the drawing apparatus. 5
14. In apparatus of the character described, the combination with the depositing apparatus, the draw plate, and means for drawing the wire from the depositing apparatus through the draw plate; of means for maintaining a uniform tension upon the wire as it leaves the depositing apparatus and a gripping device normally held inoperative by the tension of the wire on its way to the draw plate, but adapted to grip the wire when the wire breaks at the draw plate. 10
15. In apparatus of the character described, the combination of a depositing vat, supporting rolls for maintaining and carrying the wire therein, and means for effecting adjustment of said supporting rolls with respect to each other. 20
16. In apparatus of the character described, the combination of a depositing vat, supporting rolls for maintaining and carrying the wire therein, and means for varying the distance between said supporting rolls. 30
17. In apparatus of the character described, the combination of a depositing vat, supporting rolls for maintaining and carrying the wire therein, and means for effecting adjustment in the angular relation of said rolls to each other. 35
18. In apparatus of the character described, the combination of a depositing vat adapted to contain the bath, a supporting frame suitably disposed above the bath, a supporting sleeve mounted therein and extending downward normally below the level of the bath, a shaft in said sleeve, means for supporting said shaft, a hollow cylinder closed at the bottom but open above suitably secured to the bottom of said shaft, and enclosing a portion of said supporting sleeve and bearings disposed between said supporting sleeve and said hollow cylinder. 40
19. In apparatus of the character described, the combination of a depositing vat adapted to contain the bath, a supporting frame suitably disposed above the bath, a supporting sleeve mounted therein and extending downward normally below the level of the bath, a shaft disposed within said supporting sleeve, means for supporting said
- shaft a hollow cylinder closed at the bottom but open at the top suitably secured to the lower end of said shaft and surrounding said supporting sleeve, bearings mounted between the sleeve and hollow cylinder, and a collar loosely surrounding said supporting sleeve and closing the upper end of said hollow cylinder. 45
20. In apparatus of the character described, the combination with a depositing vat, suitably mounted supporting rolls for maintaining and carrying the wire therein, and a driving connection therefor; of rotary guide devices for guiding the wire to said rolls and automatic means associated with said rotary guide devices for interrupting said driving connection upon the escape or projection of the wire from its normal position in said rotary guide device. 50
21. In apparatus of the character described, the combination with a depositing vat, suitably mounted supporting rolls for maintaining and carrying the wire therein, adapted to conduct electric current from the wire, and anode plates having suitable electrical connections and mounted in proper relation to the wire between said supporting rolls; of an insulating screen extending across the vat between the anode plates and the supporting roll at each end of the vat, having restricted passageways through which the wire runs. 55
22. In apparatus of the character described, the combination with the depositing vat, suitably mounted supporting rolls for maintaining and carrying the wire therein and adapted to lead current from the wire, and anode plates arranged at either side of the wire in each side of the vat between said supporting rolls forming lanes through which the wire travels; of a screen disposed across the vat between the anode plates and the supporting roll at each end of the vat, having restricted wire passages in line with the lanes formed by said anode plates, means for introducing the fresh electrolytic bath into the end compartments of the vat formed by said screens, whereby the circulation of the fresh bath occurs through said restricted wire passages and said lanes between the anodes, and means for withdrawing the bath from the lower portion of the vat between said screens. 60
